UNITED STATES PATENT OFFICE.

EDWARD H. BAUGH AND CHARLES W. SELVIDGE, OF MEXIA, TEXAS.

HOISTING ATTACHMENT FOR WAGON-BEDS.

SPECIFICATION forming part of Letters Patent No. 496,471, dated May 2, 1893.

Application filed December 31, 1892. Serial No. 456,853. (No model.)

To all whom it may concern:

Be it known that we, EDWARD H. BAUGH and CHARLES W. SELVIDGE, citizens of the United States, residing at Mexia, in the county 5 of Limestone and State of Texas, have invented certain new and useful Improvements in Hoisting Attachments to Wagon-Beds; and we do hereby declare that the following is a full, clear, and exact description of the same, 10 reference being had to the annexed drawings, making a part of this specification, and to the letters of reference marked thereon.

The present invention has for its object to provide a hoisting attachment to wagon beds 15 that can be quickly and easily connected thereto and as readily removed when not in use, and is simple in construction with the necessary strength to support the weight of the wagon bed and is capable of being manufactured at a comparatively small cost so as 20 to bring it within the reach of those requiring such a device.

The above objects we attain by a device constructed substantially as shown in the drawings and hereinafter described and claimed.

Figure 1 of the drawings represents a perspective view showing our improved device applied to a wagon bed. Fig. 2 a detail view of the device partly in section and on an enlarged scale. Fig. 3 a detail sectional view taken on line *y* *y* of Fig. 2.

In the accompanying drawings A represents the wagon bed and B the overhead beams of rafters upon the interior of a barn, stable or 35 wagon-house, as the case may be, which have connected to them suitable pulleys *a* *b*, these parts being shown simply to better illustrate the application and use of the hoisting device which alone forms the subject of my 40 invention.

The device consists in part of a cast or wrought metal frame C having its lower end bifurcated as shown at D in Fig. 1, to which are connected chains or ropes *c* provided at 45 their outer ends with suitable hooks *d* to catch over the projecting ends of one of the sills H of the wagon bed.

The frame C is provided with a windlass E which is connected to a shaft *e*, said shaft 50 having its bearings in the sides of the frame and having connected to one end a suitable

handle F for operating the windlass which revolves with the shaft. The windlass is provided at one end with the usual ratchet *f* with which engages a pawl *g* pivoted to the frame 55 of the device. The rope *h* which is connected to the windlass passes up through a central hole *i* in the upper end of the frame C and thence over the pulleys *a* *b* after which the free end of the rope is connected in any suitable manner to the opposite end of the wagon-bed, either by looping it around the same as shown, or in any other preferred way as found most desirable, and in this position the wagon-bed is elevated by turning the windlass and 60 winding the rope thereon. The central hole *i* forms a guide for the rope when the windlass is being turned and the bifurcated end D forms a strong and simple means of attaching the ends of the ropes or chains to which the 65 hooks are connected. After the hooks *d* are engaged with the projecting ends of the sill some means should be employed for holding the device in position on the end of the wagon-bed while the rope *h* is being engaged with 70 the pulleys and the opposite end of the wagon-bed. In order to attain this end a very simple and practical attachment is employed that will adapt itself to the end-gate of the wagon bed and consists in a swivel connection, 75 embracing a hook G which is swiveled to the frame C in the following manner. On the upper end of the frame near one side are lugs *k* for pivotally supporting the ends of a head or bar *l* and through this bar loosely passes the 80 shank of the hook G which is headed upon its end to prevent it from pulling out, thus swiveling the hook to the frame and enabling said hook to adapt itself to any projections upon the outside of the end-gate so that the hook 85 in any case can be made to engage with the upper edge of the gate to support the frame C while the rope is being connected to the pulleys and opposite end of the wagon-bed.

Any suitable form of swivel hook may be 90 used and any means may be employed for forming a swivel connection between the hook and the end of the frame, and any changes or modifications may be made in the details of construction as would come within the scope 95 of the invention.

Having now fully described our invention,

what we claim as new, and desire to secure by Letters Patent, is—

5 A hoisting device for wagon beds, consisting of a suitable frame, a windlass connected thereto, a hoisting-rope attached to the lower end of the frame and having hooks to engage with the sill of the wagon-bed, said frame having a hole at its upper end for the hoisting rope, and a hook connected to the frame 10 and adapted to engage the upper edge of the

end-gate of the wagon-bed, substantially as and for the purpose set forth.

In testimony that we claim the above we have hereunto subscribed our names in the presence of two witnesses.

EDWARD H. BAUGH.
CHAS. W. SELVIDGE.
